UNITED STATES PATENT OFFICE.

ELMER P. NICHOLS, OF MANCHESTER, NEW HAMPSHIRE, ASSIGNOR TO
LACENE MANUFACTURING COMPANY, OF MANCHESTER NEW HAM-
SHIRE, A CORPORATION OF MAINE.

EVENING AND GRADING MACHINE.

No. 841,809.

Specification of Letters Patent.

Patented Jan. 22, 1907.

Application filed March 9, 1903. Serial No. 146,817.

To all whom it may concern:

Be it known that I, ELMER P. NICHOLS, a citizen of the United States, residing at Manchester, county of Hillsboro, State of New Hampshire, have invented an Improvement in Evening and Grading Machines, of which the following description, in connection with the accompanying drawings, is a specification, like letters on the drawings representing like parts.

My invention is a machine for evening and grading soles, taps, counters, &c., for shoe manufacture and capable of adaptation to various other uses, the present invention being an improvement on the kind of device shown and claimed in my Patent No. 711,585, granted October 21, 1902, which is the pioneer in this art for automatically-setting mechanism for evening leather and for automatically-setting mechanism for grading leather. The machine therein shown, however, sets the mechanism for operating on the leather with reference solely to the thinness of the leather at one point, that point being the place detected by the feeler at the instant when the gaging mechanism is tripped, and is incapable of setting the operating mechanism so as to even or grade the leather to a uniform thickness, or, in other words, it is incapable of setting the mechanism down to the thinnest portion of the stock or with relation to the thinnest portion of the stock.

It is very desirable and in many instances essential that the automatic gaging of the stock should take place with reference to the thinnest portion thereof, or at least to the thinnest portion of a certain part of the piece of leather—as, for example, it is essential that cut soles should be gaged with reference to the thinnest portion of the toe end, and, furthermore, the best class of cut soles should be gaged with reference to their edges, in order to give perfect sole-rounded and finishing effects when applied to shoes.

Accordingly among the leading objects of my invention are the provision of mechanism which, if desired, may be relied upon for automatically grading or evening the leather to the thinnest portion; means for following the contour and gaging the material adjacent both edges; means for permitting the entire length of the piece of material to be traversed, if desired, before setting the gage; adjusting means permitting the gage to be locked or set for any portion of the stock desired; means for requiring the stock to be fed

at a definite point in the rotation or movement of the machine, thereby insuring uniformity of marking; an automatic marker for indenting or stamping the graded pieces with a die, and other improvements, such as means for positively and accurately setting the grading-roll, &c.

Viewed in its broadest features the machine which embodies my invention comprises means for permitting the stock to pass in gaging relation to means for detecting the condition of the stock as to its thickness or thinness, and thereby automatically adjusting the mechanism which operates upon the stock with relation to the said condition found to exist either throughout the whole portion of the stock or any desired part or area thereof, and then the stock-operating mechanism treats the stock in accordance with said automatic gaging—as, for instance, it cuts or evens off the stock to a uniform thickness or to a uniform thickness for a desired portion thereof, or it classifies or grades the successive pieces of stock with reference to the automatic gaging aforesaid, so that all the pieces of one condition may be distinguished from the others, and while these various operations may be accomplished in various ways I prefer to embody them all in one machine, as herein shown. In some instances it is desirable, however, to have the grading mechanism embodied in a machine by itself, so that the soles, for example, which have been automatically branded or classified in such a way as to permit the corresponding grades to be bunched together may be thereafter run through an ordinary skiving-machine, said machine being set by hand to one grade for the entire bunch of soles of that grade and then set to another grade for the next bunch or package of soles. This is only one of the various sub-combinations or modifications included herein.

All the above and further objects of my invention will be manifest from the following description of the constructional details and operation of the machine, taken in connection with the accompanying drawings, in which I have shown a preferred embodiment of the invention, and the latter will be more particularly defined in the appended claims.

In the drawings, Figure 1 shows in side elevation a machine embodying the invention. Fig. 2 is a cross-sectional detail thereof, taken on the line 2, Fig. 6. Fig. 3 is a detail in side

elevation of one of the edge followers and feeler-carriers. Fig. 4 is a vertical cross-section taken on the line 4 4, Fig. 1. Fig. 4^a is a detail in rear elevation showing the guard 5 of the gaging mechanism. Fig. 5 is a side elevation of the machine viewed from the left-hand side, the driving-shaft being shown in section. Fig. 6 shows the machine in front elevation. Figs. 7 and 8 show, respectively 10 in front elevation and top plan, the upper roll-carrying frame. Fig. 9 is a top plan view of the machine.

In its general construction and plan of operation my present machine resembles the 15 patented machine above referred to, in that it contains feed-rollers, gaging mechanism, grading or marking mechanism, and evening means, the pieces of stock being fed in between feed-rollers and engaged by feelers or 20 gage-adjusters and thence fed to the mechanism which operates upon it according to the determination of the gaging mechanism, the leading feature of difference, however, being that my present machine treats the 25 leather with reference to the thickness of the entire piece or a given area thereof.

While I have shown specific mechanism and have herein described the same in detail for accomplishing the various results, I desire 30 to point out that the broad features of the invention, considered as such, are not to be confused with the mechanical details, but may be embodied in a wide variety of mechanisms, said broad features including means 35 for automatically determining all the unevennesses of the leather and preserving the concrete result of said entire determination, so that thereupon the leather may be treated with reference to this automatic determination. As the feelers detect the differences in 40 condition of the stock at successive points over its entire area or a given portion thereof, the gaging or adjusting mechanism receives and preserves all the successive adjustments determined by all the thin spots, for instance, passed over by the feeling means, and then when the leather has been felt of over the prescribed surface this gaging mechanism, which has thereby been automatically 45 adjusted to correspond to the thinnest portion passed over by the feelers, immediately correspondingly adjusts the mechanism which is provided for operating upon the stock, such as the cutting means and the 50 grade-designating or grade-distinguishing means or whatever means may be provided for engaging or acting upon or with reference to the stock whose grade has been ascertained.

55 The leather is fed between upper and lower feed-rolls a a' , the former being mounted in journal box or carrier a^2 , Figs. 7 and 8, movable up and down in guideways a^3 and carrying, as herein shown, a pair of feelers a^4 a^5 of special pattern, these feelers being loosely

mounted on the shaft of the roll, as clearly shown at a^6 , and having lower bearing ends a^7 for resting on the upper surface of the leather. These feelers or detectors detect the thin spots with relation to whose grade 70 or level the leather must be shaved or cut off so as to get it all reduced to one uniform thickness, and in order that there may be no possibility of defective results in this respect they are placed properly in relation to means 75 for pressing or holding the leather flat down and smoothing out the wrinkles and unevennesses due to the natural tendency of leather to curl or bend when permitted to do so, and while this arrangement of parts may be provided at any desired place in the machine it is most convenient to have it located at the feeding-rolls themselves, and also as in handling certain kinds of stock—as, for instance, shoe-soles—it is advisable to have the detectors 80 operate on particular portions thereof, especially along the edges, I have mounted the feelers at the feed-rolls in edge followers a^8 , which serve as holders or carriages for the feelers, as clearly shown in Figs. 2 and 3, 85 90 the engaging ends thereof traveling in longitudinal slots in the journal box or carrier, so that the under side of the latter and the feed-roll a serve to maintain the leather piece absolutely flat at the point of the engagement 95 therewith of the feelers and edge followers. The latter are connected together by springs a^9 (see Figs. 6 and 9) and have on their lower sides depending legs or edgers a^{10} , said 100 holders or edge followers being slidably mounted on opposite fixed rods a^{12} a^{13} , separated, as shown, for giving steadiness and freedom of sliding movement for permitting the feelers to maintain proper position under all circumstances.

105 The legs or edgers a^{10} bear against the opposite edges of the strip and cause the feelers to follow the contour of the sole or other piece of material being gaged, the feelers because of their loose mounting on the shaft of the roll a being free to rise and fall, thereby detecting the thin spots and the edgers co-operating therewith to detect the thin parts along the edges.

110 The respective feelers carry at their respective ends rack-bars a^{14} as a convenient means of operating the gaging devices, said rack-bars being in engagement with segmental racks a^{15} on a shaft a^{16} , provided with a rigid lever a^{17} , connected by a link a^{18} to a 115 shield-plate or guard a^{19} , arranged underneath the machine for convenience and co-operating with a rack a^{20} on the upper side of a slide-bar a^{21} and with a pawl a^{22} , carried by a slide-bar or carrier a^{23} , to regulate the setting of the gaging mechanism. The bar a^{21} is also provided with a rack a^{24} in engagement with a gear a^{25} , carrying eccentrics or cams a^{26} on a shaft a^{27} , journaled beneath the outgoing end of the machine, for adjusting 120 125 130

the stock treating or engaging mechanism, the latter being herein shown as consisting of grading apparatus for distinguishing or classifying one grade of leather from another 5 and evening mechanism for reducing the stock to the thickness desired.

The plan of operation is that as the feelers detect the stock they automatically govern the gaging mechanism, which has just been 10 described, and at the proper moment the latter is automatically set and is then caused to adjust the stock-treating apparatus in accordance with the thinness of the area of the stock detected. The cams a^{26} engage adjustable studs a^{28} , mounted in yokes a^{29} , connected by bolts a^{30} to the journal-boxes a^{31} of the upper gage-roll a^{32} , normally under tendency 15 to rise by means of springs s , the stock being held up thereto by a lower roll a^{33} in position to be engaged by a cutting-knife or other cutting mechanism a^{34} . This construction 20 co-operates with the other mechanism to insure uniform and accurate evening of the stock, as it prevents any possible movement 25 of one end of the gage-roll relatively to the other end or any improper shifting of said roll, because the gage-roll is held rigidly against upward movement, being connected unyieldingly by the tie-bars a^{30} and yoke a^{29} 30 with the studs a^{28} bearing on the under side of the cams.

The segmental racks a^{15} are mounted to turn freely on the shaft a^{16} when moving upwardly; but they engage said shaft to rotate 35 the same when moving downwardly by any convenient mechanism, being shown in Fig. 9 as provided with shouldered lugs a^{35} , adapted to engage oppositely-shouldered lugs a^{36} of a central block a^{37} , fast on the shaft a^{16} , so that 40 the feelers can move freely upwardly without changing the gage-setting device when any thick portions of leather pass beneath them, but will delicately adjust said gage-setting mechanism to the thinnest point which may 45 come beneath either of them.

To regulate the extent of the material for whose thinnest portion the gaging mechanism is to be adjusted, I provide means for preventing the aforesaid automatic detecting 50 mechanism from operating for a given portion of the length of the stock or, in other words, I provide means for rendering the same inoperative for such portion of the stock as may be desired, said means being herein 55 shown as comprising a locking roll or device a^{38} , mounted in a hanger a^{39} , adjustably secured to the outturned end of a rod a^{40} , whose other end (see Fig. 9) is provided with a depending bar or strip a^{41} , normally in 60 pressing engagement with a detent or pawl a^{42} , (pivoted on the frame beneath the guard a^{19} , see Figs. 1 and 6,) adapted to be held upward by a spring a^{43} (whenever the pressure of said trip is removed therefrom) to engage a rack a^{44} on the under side of the guard

a^{19} . Thus until the piece of stock is fed forward sufficiently to strike the locking device a^{38} the gaging mechanism is not permanently adjusted by the feelers to any thickness, inasmuch as the guard a^{19} moves freely back and forth without any permanent result; but as soon as the piece of stock engages and lifts the device a^{38} the trip a^{41} is thereby lifted from the detent a^{42} , so that thereafter the guard a^{19} can move to the right only or, in other words, can receive such adjustment only as is caused by the downward movement of the feelers, thereby transmitting and retaining all the successive increments of adjustment as each successively thinner spot is detected. Hence when the pawl a^{22} is reciprocated it will be permitted by said guard to engage with the teeth of the rack a^{20} at a point corresponding to the thinnest portion of the stock fed through beneath the feelers. 85

The strip of leather is fed forward by any suitable feeding mechanism, an endless sprocket-chain feed b being herein shown, and in order that the mechanism for operating upon the stock may be set in accordance with 90 the aforesaid adjustment of the gaging mechanism it becomes necessary to set or fix the gaging mechanism. For accomplishing this result I provide that as the stock is fed forward its forward end operates a gage-setting 95 mechanism, preferably of the automatic-clutch type, herein shown as a setting-roll c , adjustably mounted by hangers c' on a rod c^2 , journaled at c^3 above the rod a^{40} and connected at its opposite end at c^4 by a bar c^5 to 100 a lever c^6 , pivoted at c^7 to the frame and normally resting against a dog c^8 , mounted at c^9 on the inner face of a wheel c^{10} , adapted to engage a clutch c^{12} , continuously rotating on a shaft c^{13} , said clutch being carried by a 105 sleeve whose pinion c^{14} is driven by a gear c^{15} , fast on a sprocket-wheel c^{16} , driven by a sprocket-chain c^{17} , passing over the main driving-shaft c^{18} .

The operating of the setting-roll c , as 110 stated, causes the wheel c^{10} and its shaft c^{13} and disk c^{10} to be thrown into clutched engagement with the continuously-running mechanism of the machine, as stated, so that thereby the pawl-carrier a^{23} is forcibly reciprocated, and its pawl a^{22} is permitted to engage the rack-bar a^{21} , according to the position of the guard with relation to the teeth thereof, whereupon the movement of the rack-bar a^{21} acts through its rack a^{24} to 115 rotate the cams a^{25} , and thereby accurately set the gage-roll a^{32} .

The normal position of the parts is as shown in Fig. 1, the arrangement being such that the wheel c^{10} performs one revolution 120 and is then automatically permitted to stop, this provision insuring that the setting movement shall be invariably correct whether the thickness determined be less or greater than that of the preceding piece of leather fed 130

through the machine, and the first movement of the pawl-carrier a^{23} is to the right, its end engaging a shoulder a^{45} of the bar a^{21} and moving the latter with it, so as to permit the gage-roll to be separated from the knife and also insure that the parts will be set to the thickness determined by the feelers whether said thickness be less or greater than the determined thickness of the preceding piece fed through the machine, the movement of the pawl-carrier a^{23} being reversed when the disk c^{100} has passed a semi-rotation, said disk continuing its rotation until it again reaches the point shown in Fig. 1; when the clutch is automatically thrown out by the engagement of the dog c^8 with the lever c^6 , which has meanwhile dropped into its normal position by the disengagement therewith of the bar c^5 , (said bar being mounted on the frame of the machine to slide freely lengthwise for lifting the lever c^6 , but held against movement to the left therewith, Fig. 5, so that when said lever is lifted to a certain extent the previously engaging notches 25 of the lever and bar automatically disengage, permitting the lever to drop, the same in principle as in my previous patent.)

The under feed-roll a' is driven by the gear c^{15} , which meshes with a gear c^{19} on the shaft 30 of said roll, said shaft at its opposite end being provided with a pinion c^{20} , meshing with a gear c^{21} , provided at its outer face with a pin c^{22} , adapted to engage once in every revolution with one arm of a bell-crank lever c^{23} , whose other arm carries a segmental rack c^{24} , in engagement with a gear c^{25} , meshing with a ratchet-gear c^{26} on a shaft c^{27} , carrying a disk c^{28} , provided with opposite lifting pins or projections c^{29} c^{30} , adapted to engage, successively, the projecting or overhanging cap-plate or arm c^{31} of the stamping-frame c^{32} c^{33} , to the rear lower end of which is journaled a dial-like die-wheel c^{34} , which carries on its edge, in relief, the numbers or characters to be stamped into the leather and on its face proper figures or reading matter to indicate to the operator the position to which it has been set.

The setting mechanism for this dial or marking device comprises in the embodiment herein shown a gear c^{35} , fast on the shaft which carries the eccentrics a^{26} , said gear meshing with a pinion c^{36} , (see Figs. 5 and 6) in mesh with the beveled pinion c^{37} at the lower end of a shaft c^{38} , provided at its upper end with a sprocket-wheel c^{39} , engaged by a sprocket-chain c^{40} (see Fig. 9,) passing over a sprocket-wheel c^{41} , in which freely slides a shaft c^{42} , to which said wheel c^{41} is keyed, said shaft c^{42} at its lower end being provided with a bevel-gear c^{43} , meshing with a gear c^{44} on said dial c^{34} , thereby insuring that the dial will be set in exact accordance with the adjustment of the gage-roll by the eccentrics a^{26} .

I prefer to cause the marking mechanism to deliver a hammer-like die impression upon the leather and for this purpose have provided the lifting devices or cam-pins c^{29} c^{30} , which permit the marking device to be suddenly released, and I also employ means for driving the same downward forcibly, herein shown as an arm c^{45} , pivoted at c^{46} and held under strong downward pressure by a spring c^{47} .

The stamping mechanism and setting mechanism, &c., are caused to operate at the proper time by reason of the fact that the time of feeding the pieces of leather to the machine is regulated in that embodiment of my invention which is herein set forth.

I have provided on the inner face of the wheel c^{21} a pin c^{48} , which controls the time at which the feeding can take place, said control being herein shown as by means of a gate c^{49} , carried on an arm c^{50} , projecting rearwardly beyond its pivot c^{51} in the path of said pin c^{48} , so that when the proper time arrives for feeding a strip to the feed-rolls the gate will be lifted momentarily to permit the strip to be quickly shoved between the feeding-rolls, and will then drop, barring further feeding until the time therefor comes around again.

The main shaft c^{18} has a pinion c^{52} at its far end, Fig. 9, in mesh with a gear c^{53} on the shaft of the pressure-roll a^{33} , and at its near end the driving-shaft c^{18} has a gear c^{54} , in mesh with an idler c^{55} , which drives a gear c^{56} , fast on the shaft of the gage-roll a^{32} .

Adjacent the hub of the gear c^{53} is a sprocket-wheel c^{57} , which drives, by means of sprocket-chain c^{58} , a shaft c^{59} , whose sprocket-wheel c^{60} drives the feed-chain b of the machine.

In describing my invention I have already set forth in a general way the operation of the machine, which may be summarized as follows: The operator stands at the front of the machine with the stock ready, and the moment that the gate c^{49} is raised he shoves the stock to the feeding-rolls, which grab the same and carry it forward beneath the feelers, which follow along the opposite edges of the stock and rise and fall according to the changing thickness thereof. As one or the other feeler falls its lug a^{36} engages the adjacent projecting shoulder a^{36} of the shaft a^{16} and through the connecting mechanism shifts the guard a^{19} to the right, Fig. 1, this gradual shifting of said guard to the right taking place by successive increments as each successively-thinner spot is detected by either or both of the feelers as the stock is being fed along. This adjustment of the gagging mechanism is automatically retained or made certain by the locking mechanism, which prevents the guard from being shifted to the left. The feelers as herein arranged may be rendered active or operative throughout the whole length of the stock being fed or

for a limited portion thereof, according to the desire of the operator, so that they will detect and set the gaging mechanism for the thinnest spot of the entire piece or of a pre-determined area thereof, according to the wishes of the operator. If he wishes to set the machine so that the locking mechanism will be operative for a portion only of the length of the stock, he simply adjusts the locking-roll along its supporting-rod. For instance, it frequently happens that the heel end of a sole is thinner than the thinnest portion of the fore part, this undue thinness not, however, being seriously objectionable in shoe manufacture, as it comes at the heel end, where it is not subject to wear, being covered by the heel, and accordingly instead of reducing the whole sole to the thickness of the thin heel end, which would waste unnecessarily this expensive stock, the machine is set so that the automatic evening and grading mechanism will operate only for the fore part of the sole and will not grade relatively to the thinner heel portion. In this case the sole is fed heel first, and the locking-roll is adjusted far enough from the feelers to permit the heel end of said sole to have passed beyond the feelers before the stock engages the locking-roll, and therefore the gaging mechanism will be operated only for that portion of the sole thereafter in engagement with the feelers.

The setting-roll is preferably adjusted so that when the rear end of the stock is just passing from beneath the feelers the front end thereof will engage with said setting-roll. The stock having been fed beneath the feelers and the gage-adjusting mechanism correspondingly shifted, the stock continues forward until it escapes from beneath the setting-roll, whereupon the gaging mechanism is set in operation, and by the time the stock reaches the same the gage-roll has been set accurately to the thinnest point detected by the mechanism already described. Also just prior to the stock reaching the cutting mechanism the die or marking apparatus has been automatically set to correspond to the setting of the gage-roll, and as the stock passes beneath the same the tripping mechanism thereof is released, permitting the die to stamp the stock properly.

It is necessary that the gate c^a and other main features of the machine shall operate in synchronism, by which I do not necessarily mean in unison or simultaneously, but that one shall operate as often as the other, the mechanism being provided to insure that for every piece of stock that is let into the machine by the raising of the gate the setting mechanism shall operate once, and the dieing mechanism shall also operate once at the proper time to die the piece of stock that has reached it and the grading or evening mechanism shall be set.

By providing the form of feelers and guiding arrangement thereof shown I am enabled to insure that the stock shall have a uniform thickness throughout its entire perimeter, which is of particular advantage in shoe-soles. 70

By having the gate or automatic feeding control described I am enabled, besides the other advantages thereof already mentioned, to insure that all the pieces of stock will be properly evened, inasmuch as it is impossible for an operator to feed one piece of stock to the machine before the preceding piece is properly out of the way. 75

The provision whereby the feelers are brought in vertical alinement with the axis of the top roll a' is of value, as it insures that the stock will be engaged by the feelers at the point where it is held down flat against the bottom roll, or, in other words, there is no chance for inaccurate or improper gaging of the stock, inasmuch as the two rolls necessarily pinch or straighten the stock out flat and the feeler or feelers engage the same at this very point. 85

By the term "grading" I mean either designating, as by marking, or in any other way differentiating or classifying the different grades of stock. 90

On some of its features, as already intimated, I intend to base broad claims—as, for instance, in certain of my claims, where it will be noticed that I have omitted some features of the machine—the reason therefor being that advantageous commercial results may be produced by the subcombinations of parts, omitting the other parts or using said subcombinations with new or additional parts. 95

By removing the knife or whatever form of dressing or evening mechanism is provided the machine will grade and mark stock rapidly and accurately, and this is also true where the preferred form of feeler or detecting mechanism shown in my present drawings is used or the apparatus shown in my before-mentioned patent or modifications of either of these, the mechanism shown in my present drawings affording, however, greater variety of adjustment, especially as to the extent of stock or proportion of each piece over which the grade-setting mechanism may operate, and it will be understood that the gaging mechanism may be employed in connection with any other device which it may be desired to operate upon the stock in accordance with the gaged results of the feelers or detecting devices. 110 115 120

For lack of a better generic term to cover the mechanism which is gaged I call it the "leather-engaging" means or "grade-indicating" means, as its primary office is to engage the leather pieces for the purpose of usefully perpetuating the determinations of the feeler means. The leather-engaging means or grade-indicating means serve to classify the leather either directly or indirectly by mark- 125 130

ing it with a readable symbol, altering its thickness, surface, or weight to a measurable extent or in some way bringing in a distinguishing element in connection with the leather piece, whereby the result of the feeler-detecting is indicated to the operator or is otherwise made available.

A further feature which conspires with the rest to insure uniform and accurate evenness of the stock is the positive setting of the gage-roll, which, it will be seen, is held rigidly against upward movement by the tie-bars a^{30} , yoke a^{29} , and studs a^{28} bearing directly against the cams strongly mounted in the frame. This prevents any possible movement of one end of said gage-roll relatively to the other or any shifting in position.

It will be understood that I have herein described my invention in its preferred embodiment only and that it is capable of wide variety of mechanical embodiments without departing from the spirit and scope of the invention in its broader features and as covered in certain of the less-restricted claims appended hereto, and while my present invention is subordinate in its general idea and foundation principles to my before-mentioned patent it contains also certain broadly new features, as will be more apparent from the claims, and accordingly I do not intend to restrict myself otherwise than as expressed in said claims, taken in connection with the rest of the specification.

This case is intended to cover generically the broad features of invention which are common to the specific constructions in my copending applications, Serial Nos. 219,755, 257,587, and 325,224.

Having described my invention, what I claim as new, and desire to secure by Letters Patent of the United States, is—

1. A machine of the kind described, comprising leather-engaging mechanism for operating upon the leather pieces, detecting mechanism arranged and operating to ascertain the thinnest spot in a considerable portion of the length of the stock, and automatic means controlled by the detecting mechanism for regulating said leather-engaging mechanism with reference to the said ascertained thinnest spot of the predetermined length of stock.

2. A machine of the kind described, comprising grade-indicating means to indicate the grade of an uneven piece of leather, means for detecting a plurality of the thin spots of a prescribed area of said leather, means for predetermining and varying the extent of the stock on which said detecting means shall operate, and automatic means constructed and operating to adjust said grade-indicating means to the thinnest of the plurality of thin spots detected in said area.

3. A machine of the kind described, comprising grade-indicating mechanism to indi-

cate the grade of an uneven piece of leather, provided with means for indicating the grade of successive pieces of leather according to the thickness of an extended length of each leather piece, and automatic mechanism for automatically detecting as the stock is being fed the thinnest spot, throughout a considerable portion of the length of the leather, over which said mechanism passes and for adjusting said grade-indicating mechanism according to the thinnest of the thin spots detected by said automatic detecting mechanism.

4. A machine of the kind described, comprising grade-indicating mechanism to indicate the grade of an uneven piece of leather, adjusting devices for adjusting said mechanism, said devices including means for detecting thin spots throughout a considerable portion of the length of the leather being fed through the machine, and setting mechanism for thereafter operating said adjusting devices according to the thinnest of the aforesaid thin spots detected by said detecting means.

5. In a machine of the kind described, mechanism to operate on the stock, means for feeding the stock thereto, and automatic means for adjusting said mechanism, including separate feelers independently movable according to the thickness of the stock, and means for locking said automatic means to correspond to the extreme position assumed at any time by either of said feelers.

6. A machine of the kind described, comprising leather-engaging means, detecting mechanism constructed and operating to detect thin spots at a plurality of points at each of the edges only of a died piece, and mechanism responsive to said detecting mechanism constructed and operating for adjusting said leather-engaging means to the thinnest of the plurality of thin spots detected by said detecting mechanism.

7. A machine of the kind described, comprising grade-indicating mechanism to indicate the grade of an uneven piece of leather, and automatic means for adjusting said mechanism, including detecting means for engaging the leather at the edges thereof constructed and operating to maintain said edge engagement irrespective of variations in contour of said edges.

8. A machine of the kind described, comprising grade-indicating mechanism to indicate the grade of an uneven piece of leather, and automatic means for adjusting said mechanism, including detecting means for engaging the leather at the edges thereof constructed and operating to maintain said edge engagement irrespective of variations in contour of said edges, and means responsive to said edge engagement for adjusting said grade-indicating mechanism according to the thinnest of the thin spots detected by said detecting means.

9. A machine of the kind described, comprising grade-indicating mechanism to indicate the grade of an uneven piece of leather, automatic means for adjusting said mechanism, including detecting means for engaging the leather along the entire length of the edges of the piece, and means for adjusting said grade-indicating mechanism according to the thinnest spot of the plurality of thin spots detected in said engagement.

10. A machine of the kind described, comprising stock-engaging mechanism for operating upon the stock, automatic mechanism including edge - thickness - detecting means constructed to detect along a crooked edge, for governing said stock-engaging mechanism with reference to the thinness of the edge portions of the stock.

11. A machine of the kind described, comprising grade-indicating mechanism to indicate the grade of an uneven piece of leather, and automatic means for adjusting said mechanism, including detecting means for engaging the leather at the edges thereof, and mechanism for causing said detecting means to follow the contour of said edges.

12. A machine of the kind described, comprising grade-indicating mechanism to indicate the grade of an uneven piece of leather, and detecting means for engaging the leather at the edges thereof, constructed and operating to maintain said edge engagement irrespective of variations in contour of said edges, and mechanism governed by said detecting means for adjusting said grade-indicating mechanism to the thickness of the thinnest portion detected thereby.

13. A machine of the kind described, comprising grade-indicating mechanism to indicate the grade of an uneven piece of leather, and detecting means for engaging the leather at the edge thereof, mechanism for causing said detecting means to follow the contour of said edges, and mechanism governed by said detecting means for adjusting said grade-indicating mechanism to the thickness of the thinnest portion detected thereby.

14. In a machine of the kind described, feeding mechanism for feeding stock, opposite feelers for engaging the opposite edges of the stock being fed, mechanism to operate on the stock, connections between said feelers and said mechanism for setting the latter by the former, and means constructed and operating to maintain said edge engagement irrespective of variations in contour of said edges.

15. A machine of the kind described, comprising a grade-marker, detecting means constructed and operating to detect a plurality of spots of varying thickness of a leather piece, and gaging mechanism responsive only to the movement of said detecting means to the thinnest of said spots detected, said gaging mechanism being constructed and operating to set said grade-marker in accordance

only with the thickness of said thinnest spot of the leather piece.

16. A machine of the kind described, comprising means for marking the grade on a leather piece, detecting means constructed and operating to detect a plurality of spots of varying thickness of said leather piece, and gaging mechanism responsive to said detecting means, constructed and operating to retain a plurality of successive increments of detected thinness as each successively-thinner spot is detected and to set said marking means to mark the leather piece in accordance with the thinnest of said plurality of spots detected by the detecting means.

17. A machine of the kind described, comprising grade-marking means for marking the grade of uneven leather pieces, means for detecting the thin spots at a plurality of distinct, separated places in a prescribed area of said leather, and automatic means responsive to said detecting means for adjusting said grade-marking means with relation to the thinnest of said plurality of spots detected in said entire area.

18. A machine of the kind described, comprising grade-marking means for operating upon the stock, and a gaging mechanism for automatically adjusting said grade-marking means, including thickness-detectors and automatic means for transmitting and retaining a plurality of successive increments of detected thinness as each successively-thinner spot is detected in said stock.

19. A machine of the kind described, comprising means for marking the grade on a leather piece, means for detecting a plurality of thin spots in a prescribed area of said leather, means for predetermining and varying the extent of the stock on which said detecting means shall operate, and automatic means constructed and operating to adjust said marking means to the thinnest of the plurality of thin spots detected in said area.

20. A machine of the kind described, comprising a marking device, provided with means for marking successive pieces of leather according to the thickness of an extended length of the leather, and automatic mechanism for automatically detecting as the stock is being fed the thinnest spot throughout a considerable portion of the length of the leather over which said mechanism passes and gaging mechanism for retaining each successive increment of thinness as it is detected and for adjusting said marking device according to the thinnest of the thin spots detected by said automatic detecting mechanism.

21. A machine of the kind described, comprising means for marking the grade on a leather piece, adjusting devices for adjusting said means, said devices including means for detecting thin spots throughout a considerable portion of the length of the leather being

fed through the machine, and setting mechanism for retaining the successive increments of thinness measurements and for thereafter operating said adjusting devices according to the thinnest of the aforesaid thin spots detected by said detecting means.

22. A machine of the kind described, comprising stock-feeding mechanism, a marking device, and automatic gaging mechanism for setting said marking device, said gaging mechanism including means for holding it set to the thinnest portion determined thereby as the stock is fed.

23. A machine of the kind described, comprising grade-marking means for marking the grade of uneven died-out leather, and automatic means constructed and operating to adjust said grade-marking means to the thinnest edge portion of the leather.

24. A machine of the kind described, comprising grade-marking means for marking the grade of a died-out piece of stock, and automatic mechanism including means for determining the thickness of said stock at a plurality of distinct, separated places for a given portion of the edge of the stock length, and means for setting said marking means with relation to the thinnest spot of said given portion at its longitudinal edges.

25. A machine of the kind described, comprising mechanism for marking the grade on a leather piece, and automatic means for adjusting said grade-marking mechanism, including detecting means for engaging the leather at the edges thereof, constructed and operating to maintain said edge engagement irrespective of variations in contour of said edges.

26. A machine of the kind described, comprising mechanism for marking the grade on a leather piece, and automatic means for adjusting said grade-marking mechanism, including detecting means for engaging the leather at the edges thereof, constructed and operating to maintain said edge engagement irrespective of variations in contour of said edges, and means responsive to said edge engagement for adjusting said grade-indicating mechanism according to the thinnest of the thin spots detected by said detecting means.

27. A machine of the kind described, comprising mechanism for marking the grade on a leather piece, and automatic means for adjusting said mechanism, including detecting means whose position is regulated in accordance with the contour of the leather piece, constructed and operating to maintain its relative position irrespective of variations in contour of the pieces being graded.

28. A machine of the kind described, comprising mechanism for evening or cutting off the thicker portions of uneven leather, means for detecting the thin spots at a plurality of distinct, separated places in a prescribed area

of said leather, and automatic means responsive to said detecting means for adjusting said mechanism with relation to the thinnest of said plurality of spots detected in said entire area.

29. A machine of the kind described, comprising mechanism for operating upon the stock, said mechanism including means for cutting off the thicker portions thereof, and gaging mechanism for automatically adjusting said operating mechanism, including thickness-detectors and automatic means for transmitting and retaining a plurality of successive increments of detected thinness as each successive thinner spot is detected in said stock.

30. A machine of the kind described, comprising mechanism for evening or cutting off the thicker portions of uneven leather, means for detecting a plurality of thin spots in a prescribed area of said leather, means for predetermined and varying the extent of the stock on which said detecting means shall operate, and automatic means constructed and operating to adjust said mechanism to the thinnest of the plurality of thin spots detected in said area.

31. A machine of the kind described, comprising leather-engaging mechanism for operating upon the stock, automatic mechanism including detecting means constructed and operating to govern said mechanism with reference to the relative thinness of a plurality of different places over an extended area of the stock, and means for preventing said automatic mechanism from operating for a given portion of the length of the stock.

32. A machine of the kind described, comprising means for evening or cutting off the thicker portions of uneven leather, provided with means for evening successive pieces of leather according to the thickness of an extended length of each leather piece, and automatic mechanism for automatically detecting as the stock is being fed the thinnest spot throughout a considerable portion of the length of the leather over which said mechanism passes and for adjusting said evening means according to the thinnest of the thin spots detected by said automatic detecting mechanism.

33. A machine of the kind described, comprising mechanism for evening or cutting off the thicker portions of uneven leather, adjusting devices for adjusting said mechanism, said devices including means for detecting thin spots throughout a considerable portion of the length of the leather being fed through the machine, and setting mechanism for thereafter operating said adjusting devices according to the thinnest of the aforesaid thin spots detected by said detecting means.

34. A machine of the kind described, comprising stock-feeding mechanism, mechan-

isni for evening or cutting off the thicker portions of uneven leather, and automatic gaging mechanism for setting said evening or cutting mechanism, said gaging mechanism including means for holding it set to the thinnest portion determined thereby as the stock is fed.

35. A machine of the kind described, comprising mechanism for evening or cutting off the thicker portions of uneven died-out leather, and automatic means constructed and operating to adjust said mechanism to the thinnest edge portion of the leather.

36. A machine of the kind described, comprising feeding mechanism for feeding a died-out piece of stock, and automatic mechanism for reducing said stock to an even thickness for a given portion of its length, said mechanism including means for automatically gaging said thickness with relation to the thinnest of a plurality of distinct, separated spots throughout a predetermined extent of each of its longitudinal edges.

37. A machine of the kind described, comprising mechanism for evening or cutting off the thicker portions of uneven leather, and automatic means for adjusting said mechanism, including detecting means for engaging the leather at the edges thereof, constructed and operating to maintain said edge engagement irrespective of variations in contour of said edges.

38. A machine of the kind described, comprising mechanism for evening or cutting off the thicker portions of an uneven piece of leather, and automatic means for adjusting said mechanism, including detecting means whose position is regulated in accordance with the contour of the leather piece.

39. A machine of the kind described, comprising mechanism for evening or cutting off the thicker portions of uneven leather, and automatic means for adjusting said mechanism, including detecting means for engaging the leather at the edges thereof, and mechanism for causing said detecting means to follow the contour of said edges.

40. A machine of the kind described, comprising mechanism for evening or cutting off the thicker portions of uneven leather, and detecting means for engaging the leather at the edges thereof constructed and operating to maintain said edge engagement irrespective of variations in contour of said edges, and mechanism governed by said detecting means for adjusting said evening or cutting mechanism to the thickness of the thinnest portion detected thereby.

41. A machine of the kind described, comprising mechanism for evening or cutting off the thicker portions of uneven leather, and detecting means for engaging the leather at the edges thereof, mechanism for causing said detecting means to follow the contour of

said edges, and mechanism governed by said detecting means for adjusting said evening or cutting mechanism to the thickness of the thinnest portion detected thereby.

42. A machine of the kind described, comprising feeding mechanism for feeding a died-out piece of stock, automatic mechanism for reducing said stock to an even thickness at its longitudinal edges, and means for preventing said automatic mechanism from operating for a given length of the stock, said mechanism including means for operating it for the remaining length of the stock.

43. In a machine of the kind described, feeding mechanism for feeding stock, a feeler for engaging said stock as it is being fed, mechanism to operate on said stock, connections between said feeler and said mechanism for setting the latter by the former, and means causing said feeler to follow the edge of the stock.

44. In a machine of the kind described, feeding mechanism for feeding stock, opposite feelers for engaging the opposite edges of the stock being fed, mechanism to operate on the stock, connections between said feelers and said mechanism for setting the latter by the former, and means for causing said feelers to follow the contour of the stock.

45. In a machine of the kind described, mechanism to operate on the stock, means for feeding the stock thereto, including an upper roll, a feeler mounted coaxially of said roll and freely movable below the same, but normally held down on the stock thereby, mechanism for operating on the stock, and connections from said feeler to said mechanism for setting the latter according to the position of the feeler.

46. In a machine of the kind described, means for flattening a piece of stock being fed thereto, a feeler for detecting thin spots in said stock, said feeler engaging the stock at the point where it is flattened, mechanism for operating on said stock, and connections between said feeler and said mechanism for setting the latter according to the position of the former.

47. In a machine of the kind described, mechanism for operating on a piece of stock, adjusting means for adjusting said mechanism, said means including a pawl and ratchet, a guard for controlling the point of engagement of said pawl with said ratchet, and means operated by the passage of said stock for limiting said guard to movement in one direction for said adjustment.

48. In a machine of the kind described, feeding mechanism for feeding stock, feelers for detecting thin portions in said stock, mechanism for operating upon the stock, gaging mechanism for adjusting said operating mechanism according to the determination of said feelers and intermittently-operating

feed-permitting means for causing the dis-simultaneous feeding of the stock and the operating of said operating mechanism.

49. A machine of the kind described, comprising grade-indicating mechanism to indicate the grade of an uneven piece of leather, mechanism for detecting the thinner portions of the stock passing through the machine, and feed-controlling means for regulating the time of feeding of the successive pieces of stock to the machine.

50. A machine of the kind described, comprising grade-indicating mechanism to indicate the grade of an uneven piece of leather, automatic means for adjusting said mechanism, said means including devices for detecting the thinner portions of the stock passing through the machine, setting mechanism for operating said automatic means according to the thickness detected by said detecting means, and means for preventing the feeding of a succeeding piece of stock to the machine to interfere with the operation of said setting mechanism for a preceding piece of stock.

51. A machine of the kind described, comprising means for marking the grade on a leather piece, automatic means for adjusting said mechanism, said means including devices for detecting the thinner portions of the stock passing through the machine, setting mechanism for operating said automatic means according to the thickness detected by said detecting means, and means for preventing the feeding of a succeeding piece of stock to the machine to interfere with the operation of said setting mechanism for a preceding piece of stock.

52. A machine of the kind described, comprising a marking device, feeding mechanism for feeding stock thereto, means for detecting thin portions of said stock, and setting mechanism for setting said marking device by said detecting means, a gate for normally preventing the feeding of stock to the machine, and means for operating said gate and marking device in synchronism.

53. A machine of the kind described, comprising mechanism for evening or cutting off the thicker portions of uneven leather, mechanism for detecting the thinner portions of the stock passing through the machine, and feed-controlling means for regulating the time of feeding of the successive pieces of stock to the machine.

54. A machine of the kind described, comprising mechanism for evening or cutting off the thicker portions of uneven leather, automatic means for adjusting said mechanism, said means including devices for detecting the thinner portions of the stock passing through the machine, setting mechanism for operating said automatic means according to the thickness detected by said detecting means, and means for preventing the feeding

of a succeeding piece of stock to the machine to interfere with the operation of said setting mechanism for a preceding piece of stock.

55. A machine of the kind described, comprising a marking device, tension means tending to move said device for forcibly marking, automatic gaging mechanism for setting said marking device according to the thickness of stock being fed, and means for releasing said tension means for moving said marking device with a hammer-like blow when set.

56. In a machine of the kind described, feeding mechanism for feeding stock to the machine, feelers for detecting thin portions in said stock, a die, automatic adjusting mechanism for said die connected with and operated by said feelers, and means for actuating said die, including a lifter passing into lifting connection with said die for positively lifting the same, and passing suddenly out of said connection when the die is lifted to permit the die to descend upon the stock.

57. In a machine of the kind described, feeding mechanism for feeding stock to the machine, feelers for detecting thin portions in said stock, a die, automatic adjusting mechanism for said die connected to and operated by said feelers, and a rotary lifter passing into lifting connection with said die for lifting the same, and passing out of said connection when the die is lifted, and means for forcibly depressing said die when released by said lifter.

58. A machine of the kind described, comprising mechanism for evening or cutting off the thicker portion of uneven leather, said mechanism including an adjustable part, and automatic means for adjusting said part according to the thickness of the leather being fed, said adjusting means including a device having an inclined surface movable into position between said part and the supporting-frame thereof, and unyielding connections for transmitting the strain directly to said frame.

59. In a machine of the kind described, cutting mechanism, a gage device movable toward and from said cutting mechanism, rods supporting said gage device and carrying a bearing, a cam journaled between said gage device and said bearing and engaging the latter, and automatic means operated by the passage of stock to said cutting mechanism for rotating said cam and thereby adjusting said gage device.

60. In a machine of the kind described, feeler mechanism for feeling the thickness of a piece of leather at a plurality of places, grade-indicating means, gaging mechanism responsive to said feeler mechanism and constructed and operating to adjust said grade-indicating means to indicate the thinnest of all of said plurality of places felt of, and

means for determining the particular portion of the leather piece for which said gaging mechanism shall be responsive.

61. In a machine of the kind described, 5 feeler mechanism for feeling the thickness of a piece of leather at a plurality of places, grade-indicating means, gaging mechanism responsive to said feeler mechanism and constructed and operating to adjust said grade-indicating means to indicate the thinness of 10 all of said plurality of places felt of, and means to vary the extent of the effective responsiveness of said gaging mechanism to said feeler mechanism.

62. In a machine of the kind described, 15 feeler mechanism for feeling the thickness of a piece of leather at a plurality of places, grade-indicating means, gaging mechanism responsive to said feeler mechanism and constructed and operating to adjust said grade-indicating means to indicate the thinness of 20 all of said plurality of places felt of, and means actuated by the leather piece for controlling the effective responsiveness of said 25 gaging mechanism to said feeler mechanism.

63. In a machine of the kind described, 30 feeler mechanism for feeling the thickness of a piece of leather at a plurality of places, grade-indicating means, gaging mechanism

responsive to said feeler mechanism and constructed and operating to adjust said grade-indicating means to indicate the thinness of 35 all of said plurality of places felt of, said gaging mechanism being normally in a non-responsive condition, and means actuated by the passage of the leather piece for rendering the same thereafter responsive.

64. In a machine of the kind described, 40 feeler mechanism for feeling the thickness of a piece of leather at a plurality of places, grade-indicating means, gaging mechanism responsive to said feeler mechanism and constructed and operating to adjust said grade-indicating means to indicate the thinness of 45 all of said plurality of places felt of, said gaging mechanism being normally in a non-responsive condition, and means actuated by the passage of the leather piece for rendering the same thereafter responsive during a pre-determined travel of the leather piece. 50

In testimony whereof I have signed my name to this specification in the presence of two subscribing witnesses.

ELMER P. NICHOLS.
